UNITED STATES PATENT OFFICE.

GEORGE P. CRAGIN, OF SPOKANE, WASHINGTON, ASSIGNOR TO IDA L. CRAGIN AND MAUDE S. MCDONALD, OF SAME PLACE.

PASTE-BOTTLE.

SPECIFICATION forming part of Letters Patent No. 650,301, dated May 22, 1900.

Application filed August 11, 1899. Serial No. 726,897. (No model.)

To all whom it may concern:

Be it known that I, GEORGE P. CRAGIN, a citizen of the United States, residing at Spokane, in the county of Spokane and State of Washington, have invented new and useful Improvements in Paste-Bottles, of which the following is a specification.

This invention relates to that class of paste-bottles employing a central water-well to receive and keep in a moist condition the brush to be used in the paste, and is designed more particularly as an improvement on the construction of bottle disclosed in my Letters Patent of the United States, dated September 12, 1899, No. 632,806.

The invention and its many advantages will appear from the following description and claims when taken in connection with the annexed drawings, in which—

20 Figure 1 is a vertical diametrical sectional view of my improved bottle with the cover removed and the brush in the water-well. Fig. 2 is a vertical diametrical sectional view of the improved bottle with parts in elevation and showing the cover and oil-pad in position closing both the well and the paste-chamber. Fig. 3 is a perspective view of the well-holder removed from the bottle. Fig. 4 is a view, partly in section, of a blank from 30 which two of the holders may be cut or formed. Fig. 5 is a vertical sectional view of the upper part of a bottle, well, and a cover constructed according to a modification.

Referring by letter to said drawings, A indicates a bottle, which may be composed of glass or other suitable material and is of the form usually employed for holding paste.

B indicates a well for holding water and may be also composed of glass or the like.

40 The bottle A is provided around its upper outer side with threads *a* to receive corresponding threads on a skirt-flange *b*, which depends from the marginal edge of the cover C. This cover may be stamped or otherwise formed from sheet metal or the like, and it has a central hole or opening *c* for the introduction of the brush, said opening being designed to come above the well B and expose the interior of the same.

50 The well B, which is preferably circular in

cross-section, is placed centrally and vertically within the paste-bottle, a socket being provided to receive the well and hold the same in position.

The socket D, as better shown in Fig. 3 of 55 the drawings, is preferably composed of lead or other pliable material which will permit of the same being easily and quickly shaped and placed in position. As a cheap and convenient way of making the holders, I take a piece 60 of lead tubing or the like of a sufficient length and diameter and stamp or cut the same as shown by the dotted lines in Fig. 4 of the drawings, after which or before a groove *d* may be formed at a sufficient distance from 65 each end. The blank thus cut and grooved should be turned so as to form the socket *e* at its upper end, and the branches *f* are bent outwardly and in a horizontal plane, so as to form legs, which rest snugly on the inner side 70 of the bottom of the bottle, with their ends against the side walls of the bottle A. It will be observed that the groove *d* formed in the material will present an annular shoulder or 75 rib *g* on the inside of the socket, upon which the lower end of the well B may rest. The height at which the well may be placed within the bottle can be regulated by the position at which the rib or rest is formed in the socket or holder. The material being pliable, this 80 rib or rest can be formed very readily and conveniently at any point desired. In some cases, where it is desirable to have the top of the well extend considerably above the top of the bottle, as shown in Fig. 5 of the drawings, the rest or socket may be made of a greater height than that employed in the other construction.

The cover C', with the depending marginal and threaded flange *b'*, (see Fig. 5,) has its 90 annular intermediate portion *h* sloping and is provided with a centrally-reduced annular portion *i'*, having the brush opening or aperture *c'*. This central elevated portion is designed to embrace the upper end of the top 95 of the well B' and extend over the upper edge thereof, an annulus *8^a*, of oil-soaked material, being placed over the upper edge of the side walls of the bottle and around the well B', and a disk *8^b*, of similar material, being employed 100

to cover the top of the well during transportation or when not intended for immediate use.

From the construction described it will be seen that I have an annular chamber for paste and a water-well centrally disposed therein. In preparing the paste for the market the socket D, when formed separately from the bottle, should be placed centrally upon the bottom of the bottle and the well then placed within the socket. The paste is then placed in the annular holder or chamber and in a little while becomes sufficiently hard to stay the socket and well in position.

15 A pad j, of oil-soaked material, is then placed on the top of the bottle and over the well or the annulus around the well and disk over the well, after which the cover is turned down on the threaded upper side of the bottle, so as to snugly hold the pad on the top of both the bottle and well or the annulus on the bottle and the disk on the well, as shown in Fig. 5, when the paste may be kept for a long period of time in a good condition for use.

25 When it is desired to use the paste, the top may be turned off and the interposed pad, as shown in Fig. 2, or the annulus and disk, as shown in Fig. 5, removed, when the brush 30 may be conveniently placed in the paste-chamber. After using the cover may be turned back on the bottle, when the well will be exposed through the opening in the center of cover, and a brush may be placed in the well, where it will be kept in a soft and 35 pliable condition and always ready for use.

Having thus described my invention, what I claim is—

1. A paste-bottle having a socket arranged 40 on the inner side of its bottom to receive a well; the said socket having a lateral bearing on the bottom of the bottle whereby it is anchored in position by the paste contained in the bottle, substantially as specified.

45 2. The combination of a paste-bottle having

exterior threads at the upper edge of its side wall, a socket arranged on the inner side of the bottom of the bottle and having a lateral extension bearing on said bottom whereby it is anchored in position by paste placed in 50 the bottle, and also having an internal rib, a water-well arranged in the socket and resting on the internal rib thereof, and extending above the bottle, and a cover having a depending, threaded flange engaging the 55 threads of the bottle and also having a central aperture over the water-well, substantially as specified.

3. A paste-bottle having a socket arranged on the inner side of its bottom to receive a 60 well and provided with feet or flanges extending to the side walls of the bottle, whereby it may be held concentrically therein, and anchored in position on the bottom of the bottle by the paste contained therein, substantially as specified.

4. The combination of a paste-bottle, a well, and a socket receiving the well and arranged on the inner side of the bottom of the bottle; the said socket having a lateral extension at its base bearing on the bottom of the bottle, whereby it is anchored in position by the paste contained in the bottle, substantially as specified.

5. The combination of a paste-bottle, a 75 socket arranged on the inner side of the bottom of the bottle, and having a lateral bearing on the bottom of the bottle whereby it is anchored in position by paste placed in the bottle, and also having an internal rib, and 80 a water-well arranged in the socket and resting on the internal rib thereof, substantially as specified.

In testimony whereof I have hereunto set my hand in presence of two subscribing witnesses.

GEORGE P. CRAGIN.
